UNITED STATES PATENT OFFICE.

LOUIS P. NASH, OF ORANGE, NEW JERSEY.

CANDLESTICK.

1,138,240.

Specification of Letters Patent.

Patented May 4, 1915.

Application filed December 28, 1914. Serial No. 879,238.

To all whom it may concern:

Be it known that I, LOUIS P. NASH, a citizen of the United States, and residing at Orange, in the county of Essex and State of New Jersey, have invented certain new and useful Improvements in Candlesticks, of which the following is a specification, such as will enable those skilled in the art to which it appertains to make and use the same.

This invention relates to candlesticks, and the object thereof is to provide an improved device of this class which is designed to hold candles of different lengths and in which the candle, when in use, is entirely concealed except the burning tip thereof; a further object being to provide a candlestick of the class specified in which the candle is always supported at the same height by a spring placed within the stick and which will be ornamental, strong and durable and in which the stick is composed of a single tube formed integrally with or permanently connected with the base and the top portion of which is screw-threaded and adapted to receive a threaded sleeve provided with a shade holder; and with these and other objects in view the invention consists in a candlestick constructed, as hereinafter described and claimed.

The invention is fully disclosed in the following specification, of which the accompanying drawing forms a part, in which the separate parts of my improvement are designated by suitable reference characters in each of the views, and in which:

Figure 1 is a side view of my improved candlestick complete and showing a shade holder with the shade indicated in dotted lines; Fig. 2 a central vertical section through the candlestick including the shade holder; and, Fig. 3 a view similar to Fig. 2 but showing only a part of the device and showing the same on an enlarged scale.

In the practice of my invention, I provide a candlestick a , comprising a base a^2 , a main candlestick portion a^3 connected with the base and a supplemental candlestick portion a^4 formed integrally with the main candlestick portion a^3 . The main candlestick portion a^3 is reduced in size at a^5 and the supplemental candlestick portion a^4 is of less transverse dimension than the main candlestick portion, and placed thereon is a removable sleeve b made of porcelain or other

earthy substance and also made to resemble a candle.

The height of the main candlestick portion a^3 is preferably about twice the height of the supplemental candlestick portion a^4 , or that part thereof on which the sleeve b is mounted, and said supplemental candlestick portion a^4 is projected above the sleeve b to form a tubular extension a^6 which is screw-threaded and adapted to receive a correspondingly threaded tubular cap c provided at its lower end with an annular bead c^2 and at its upper end with an inwardly directed flange c^3 , and the cap c is provided with a shade holder d , consisting of vertical side arms d^2 having inwardly set lower end portions d^3 which are permanently connected with the cap c , and the arms d^2 of the shade holder are provided at the top thereof with an annular cap d^4 having an outwardly and downwardly directed socket member d^5 , and the cap d^4 is adapted to support a shade e indicated in dotted lines in Fig. 1. The shade holder in itself, however, forms no part of my invention and is of a form well-known in this class of devices.

At the top of the main candlestick portion a^3 is secured the usual cup-shaped collar f , in the bottom of which, the removable sleeve b fits when in position, and a candlestick constructed in this manner produces a neat and finished appearance as shown in Fig. 1. Within the candlestick is placed a long spiral spring g which is supported by a detachable plug h placed in the bottom of the main portion a^3 of the candlestick, or any suitable device may be employed for supporting the spring g , the object in making said support removable or detachable being to provide means whereby the candlestick may be thoroughly cleaned when desired. The spring g is provided at the top thereof with a beveled cap g^2 which, when the candle i is not in position is supported by said spring on a level with, or above the threaded part a^6 of the top portion a^4 of the stick, and in placing the candle in position the bottom thereof is placed on the cap g^2 of the spring g , and said spring is forced downwardly after which the shade holder cap c is screwed into position, as shown in Fig. 2, and the device is ready for use, and as the candle is consumed the spring g forces it upwardly until the cap g^2 of said spring fits beneath the flange c^3 of the shade cap c .

and in this way the entire candle may be consumed.

From the foregoing description and showing, it will be understood that candles of 5 different lengths, or of any desired length, may be used in my improved candlestick and the spring *g* may be of any desired length and strength, and springs of different lengths may be employed, if desired.

10 In the construction shown, the outer diameter of the top portion *a*⁴ of the candlestick and the removable sleeve *b* is slightly less than the outer diameter of the bottom portion *a*³ of the candlestick, or is of the 15 same dimensions as the inner diameter of said bottom portion of the candlestick, and this also adds to the artistic features of the complete candlestick, the sleeve *b* being thus made to almost exactly represent a candle 20 inserted into the bottom portion *a*³ of the stick.

Although, I prefer to make the length of the sleeve *b* approximately half the length 25 of the bottom portion *a*³ of the candlestick, as herein shown and described, my invention is not limited to these exact details, and changes in and modifications of the various features of construction herein shown and described may be made, within 30 the scope of the appended claims, without departing from the spirit of my invention or sacrificing its advantages.

Having fully described my invention, what I claim as new and desire to secure 35 by Letters Patent, is:—

1. A candle holder, comprising a base 40 adapted to rest on a table or other support and having a tubular stick contracted at a predetermined point above the base and formed into a supplemental top portion of 45 less diameter than the bottom portion, said stick being provided at the top of the bottom portion with an annular collar and the top portion being provided with a removable sleeve of less length than said top portion and which fits centrally in said collar, and the top portion of the stick being provided above said sleeve with a detachable 50

tubular cap having a shade holder and provided at its top with an inwardly directed 55 flange.

2. A candle holder, comprising a base 60 adapted to rest on a table or other support and having a tubular stick contracted at a predetermined point above the base and formed into a supplemental top portion of 65 less diameter than the bottom portion, said stick being provided at the top of the bottom portion with an annular collar and the top portion being provided with a removable sleeve of less length than said top portion and which fits centrally in said collar, and the top portion of the stick being provided above said sleeve with a detachable 70 tubular cap having a shade holder and provided at its top with an inwardly directed flange, and a spiral spring placed in said stick and provided at the top thereof with a cap adapted to support a candle placed in said stick.

3. A candle holder, comprising a base 75 adapted to rest on a table or other support and having a tubular stick contracted at a predetermined point above the base and formed into a supplemental top portion of 80 less diameter than the bottom portion, said stick being provided at the top of the bottom portion with an annular collar and the top portion being provided with a removable sleeve of less length than said top portion and which fits centrally in said collar and is of less diameter than the bottom portion of the stick and the top portion of the stick being provided above said sleeve with a detachable 85 tubular cap having a shade holder and provided at its top with an inwardly directed flange.

In testimony that I claim the foregoing as my invention I have signed my name in presence of the subscribing witnesses this 90 26th day of December 1914.

LOUIS P. NASH.
